(57) **CLAIM**

The ornamental design for an electronic cigarette mouthpiece, as shown and described.

DESCRIPTION

FIG. 1 is a front elevational view of an electronic cigarette mouthpiece showing my new design;

FIG. 2 is a rear elevational view thereof;

FIG. 3 is a left side view thereof;

FIG. 4 is a right side view thereof;

FIG. 5 is a top plan view thereof; and,

FIG. 6 is a perspective view thereof.

The front elevational view is symmetrical to the rear elevational view, and the left side view is symmetrical to the right side view.
